UNITED STATES PATENT OFFICE.

PAUL WITTECK, OF BUTLER, NEW JERSEY, ASSIGNOR TO THE BUTLER HARD BUBBER COMPANY, OF NEW YORK, N. Y.

DESIGN FOR A COMB.

SPECIFICATION forming part of Design No. 22,151, dated January 24, 1893.

Application filed December 14, 1892. Serial No. 455,197. Term of patent 3½ years.

To all whom it may concern:

Be it known that I, PAUL WITTECK, a citizen of the United States, residing at Butler, in the county of Morris and State of New Jersey, have invented and produced a new and original Design for Combs, of which the following is a specification, reference being had to the accompanying drawings, showing a part thereof.

10 Figure 1 represents a view of one of the sides of a comb representing my design. Fig. 2 is a similar view of the opposite side of the comb.

The back of the comb has a panel on each

side of it. The panel A is shaped and ornamented as shown in the accompanying drawing Fig. 1. The panel B, on the opposite side of the back, has the appearance of the drawing illustrated in Fig. 2.

15 I claim—

20 The design for a comb substantially as shown and described.

In testimony whereof I affix my signature in the presence of two witnesses.

PAUL WITTECK.
